CLAIM

The ornamental design for a container and lid for cookies or other foods, as shown and described.

DESCRIPTION

FIG. 1 is an isometric view of a container and lid for cookies or other foods of a first embodiment showing my new design; FIG. 2 is a top view of the embodiment of FIG. 1; FIG. 3 is a bottom view of the embodiment of FIG. 1; FIG. 4 is a front elevation view of the embodiment of FIG. 1, the left, right and back elevation views of the embodiment of FIG. 1 being identical to the front view of FIG. 4; FIG. 5 is an isometric view of a container and lid for cookies or other foods of a second embodiment showing my new design;

FIG. 6 is a top view of the embodiment of FIG. 5; FIG. 7 is a bottom view of the embodiment of FIG. 5; FIG. 8 is a front elevation view of the embodiment of FIG. 5, the left, right and back elevation views of the embodiment of FIG. 5 being identical to the front view of FIG. 8; FIG. 9 is an isometric view of a container and lid for cookies or other foods of a third embodiment showing my new design; FIG. 10 is a top view of the embodiment of FIG. 9; FIG. 11 is a bottom view of the embodiment of FIG. 9; and, FIG. 12 is a front elevation view of the embodiment of FIG. 9, the left, right and back elevation views of the embodiment of FIG. 9 being identical to the front view of FIG. 12.
